UNITED STATES PATENT OFFICE.

HENRY S. HAWKS, OF COLORADO SPRINGS, COLORADO.

FLUSHING-TANK.

No. 909,782.

Specification of Letters Patent.

Patented Jan. 12, 1909.

Application filed September 16, 1906. Serial No. 334,004.

To all whom it may concern:

Be it known that I, HENRY S. HAWKS, a citizen of the United States, residing at Colorado Springs, in the county of El Paso and State of Colorado, have invented a new and useful Flushing-Tank, of which the following is a specification.

This invention relates to flushing tanks.

The objects of the invention are to improve and simplify the construction of such devices; furthermore, to increase their efficiency in operation and to decrease the expense attending their manufacture.

With the foregoing and other objects in view, which will appear as the description proceeds, the invention resides in the combination and arrangement of parts and in the details of construction hereinafter described and claimed, it being understood that changes in the precise embodiment of invention herein disclosed can be made within the scope of the following claims without departing from the spirit of the invention or sacrificing any of its advantages.

In the accompanying drawings forming part of this specification:—Figure 1 is a vertical section through a flushing tank constructed in accordance with the present invention; Fig. 2 is a horizontal section on the line 2—2 of Fig. 1; and Fig. 3 is a vertical section on the line 3—3 of Fig. 1.

Like reference numerals indicate corresponding parts in the different figures of the drawings.

The reference numeral 1 indicates a tank or casing which may be of any suitable form and construction. The casing 1 is supplied with water through an inlet pipe 2 which preferably is formed with exterior threads 3. The inlet pipe 2 leads into an inlet chamber A which preferably is circular in shape and consists of the wall 4, top 5 and bottom 6. The inlet pipe 2 is threaded into the bottom 6 of the inlet chamber A, as shown, and a large washer 7 preferably is interposed between the bottom 6 of the inlet chamber A and the bottom of the casing 1. A smaller washer 8 preferably is held against the lower side of the bottom 6 of the casing 1 by means of a nut 9 so as to form a liquid-tight joint around the inlet pipe 2.

The means for controlling the flow of water from the inlet chamber A to the

casing 1 in a quick and noiseless manner, 55 preferably consists of a pair of inlet valves B and C which are adapted to be moved simultaneously in opposite directions. Each of the valves B and C preferably consists of a valve stem 10, a jam nut 11, a relatively 60 large annular plate 12, a frusto-conical rubber ring 13, a relatively small annular plate 14, and a jam nut 15. The valve seat for each of the inlet valves B and C preferably consists of a frusto-conical or flared 65 portion 16 and a straight annular portion 17, the portion 16 being adapted to receive the rubber ring 13 and the portion 17 being adapted to receive the small annular plate 14 so that said plate will serve to receive 70 the bulk of the liquid pressure, and the joint will be rendered tight by the rubber ring 13. The area of the straight annular portion 17 of each inlet valve seat is greater than the area of the inlet pipe 2, the object of which 75 is to provide a large exit from the inlet chamber A so that the water may flow into the casing 1 under a reduced pressure and without noise.

For the purpose of guiding the valves B 80 and C into proper contact with their respective seats, the stems 10 are extended loosely through perforations 18 in guide brackets 19 which are located within the inlet chamber A, the ends of said guide 85 brackets being formed with flanges 20 secured to the top 5 by means of screws 21. The guide bracket 19 for the valve C is disposed a greater distance below the top 5 than the bracket for the valve B, this construction 90 being rendered necessary by the fact that the valve C moves downwardly into the inlet chamber A during its opening movement, while the valve B moves upwardly away from the chamber A and into the casing 1 95 during its opening movement.

The means for moving the valves B and C simultaneously in opposite directions to close or open the inlet chamber A so as to permit the water contained therein to flow 100 into the casing 1, preferably consists of an operating lever D which is pivotally mounted at 22 upon a standard 23 having its lower end reduced in diameter and extended through the top 5 of the inlet chamber A, 105 said standard being held in position by a nut 24 bearing against the lower surface of the top 5 of the inlet chamber. The operat-

ing lever D preferably consists of a pair of metallic strips 25-25 which, adjacent the standard 23, are bent into parallelism with each other and fit against opposite sides of said standard, said strips being spaced apart by means of spacing sleeves 26 through which extend the attaching bolts 27. Each of the valve stems 10 of the valves B and C at its upper end extends between the metallic strips 25 and is pivotally connected therewith as indicated at 28. It will be observed that the pivot point 22 of the operating lever D is disposed intermediate the pivot points 28 of the valves B and C, so that as said operating lever is moved in one direction or the other, the valves B and C are simultaneously moved in opposite directions. Adjacent the pivot point 28 of the valve C, the metallic strips 25-25 of the operating lever D are bent so as to diverge with respect to each other, as indicated at 29, and are then bent into parallelism with each other, as indicated at 30, the parallel ends 30 being spaced away from each other, as shown, for a purpose which will presently appear.

The means for rocking the operating lever D when the casing 1 becomes empty so as to cause said lever to open the valves B and C and thus permit the casing 1 to be refilled from the inlet chamber A and pipe 2, preferably consists of a float E which is adapted to move vertically in the casing 1 and is guided in its vertical movements by means of sleeves 31 which are secured to said float 35 and slidably embrace vertically-extending guide rods 32 which preferably are mounted at their upper and lower ends in bracket members 33 suitably disposed in the casing 1. The float E preferably is provided with a false bottom 34 through which extends a stud 35 having a flared upper end 36 and being held in place by a transverse pin 37. The stud 35 at its lower end is slotted, so as loosely to receive the pivot pin 39 of an arm 40 which is connected with a cross-piece 41 extending between the spaced parallel ends 30 of the operating lever D. It will be obvious that as the water is withdrawn from the casing 1, the float E will descend by gravity and by pressing downward upon the long end of the operating lever D will move the valves B and C in opposite directions, thus causing said valves to permit water to flow from the inlet chamber A into the casing 1 until the float E rises to its highest position and causes said valves to be closed. For the purpose of regulating the depth of water in the casing 1, the pivot pin 39 of the arm 40 is made readily removable and said arm 40 is threaded, as indicated at 42, so that by removing the pivot pin 39 and rotating the arm 40 said arm can be adjusted with respect to the cross-piece 41 to regulate the distance between the lever D and the bottom of the float E, whereby said float can

be caused to close the valves B and C when the water reaches any desired depth in the casing 1.

The means of permitting the escape of water from the casing 1, preferably consists of an outlet pipe 43 which is screwed at its upper end into an interiorly threaded bushing 44 having a reduced lower end extending through an opening in the bottom of the casing 1. The bushing 44 is formed with an annular shoulder 45 which bears downward against a washer 46 resting upon the bottom of the casing 1. The lower end of the bushing 44 is exteriorly threaded to receive a nut 47 which serves to hold in position against the lower surface of the casing 1 a washer 48. The washers 45 and 48 serve to produce a water-tight joint around the bushing 44. At the same time, by removing the nut 47, the bushing 44 can be readily removed from the bottom of the casing 1 to permit said casing to be drained and repaired, if necessary. The upper end of the bushing 44 is ground or otherwise suitably finished to form a valve seat 49 adapted to be engaged by a rubber washer 50 upon the lower end of a valve stem 51. The screw 52, which extends into the lower end of the stem 51 for holding the washer 50 in position, also serves to hold in position a semi-spherical valve 53 which is adapted to fit down into the upper end of the bushing 44 to aid the washer 50 in preventing the escape of any water from the casing 1 until the members 50 and 53 are raised by means of a flushing lever 54 which is fulcrumed at 55 upon an arm 56 formed integral with a derrick frame 57 which may be of any suitable form and construction. The flushing lever 54 is pivotally connected with the slotted upper end of the valve stem 51 in any suitable manner, as indicated at 58, so that when the lever 54 is rocked by means of a cord 59 the outlet valve, consisting of the washer 50 and semi-spherical member 53, is raised to permit the escape of the water from the casing. The valve stem 51 preferably is guided in its vertical movements by means of cross-pieces 60 of the derrick frame 57, said cross-pieces being formed with perforations adapted loosely to receive the stem 51, as shown.

It will be understood that when the casing 1 is empty, the outlet valve settles down upon the upper end of the bushing 44. It may be well to state at this point that "empty" is used only in a relative sense for, as a matter of fact, the casing is never empty when the device is in proper working condition. As the water gradually rises around the outlet valve, the pressure of the water holds said valve securely against the bushing 44, even against the tendency of the valve to rise on account of the buoyancy of the floats 61 and 62. When the cord 59 is operated, however, the outlet valve is

removed sufficiently far away from the bushing 44 to be out of the influence of the suction or pressure of the water and the floats 61 and 62 will consequently cause the outlet valve to float until the proper amount of water has drained out of the tank. The water level never falls as low as the inlet chamber A, the latter therefore is always submerged and water flowing therefrom enters a body of water in the casing 1 which, in connection with the reduced pressure of the incoming water, prevents any noise. Why the water level always remains above the inlet chamber A is made plain when it is remembered that the quantity of water flowing out of the tank, when the outlet valve is opened, is governed by the float 61 which descends as the water level lowers until said outlet valve is seated; and as said float is fastened to the valve stem above the inlet chamber A, it naturally follows that the level of the water in the casing 1 can never fall lower than the float. As soon as the water begins to drain out the float E descends so as to open the inlet valves B and C and thus permit a quantity of water to enter the tank even while the outlet valve is open. For the purpose of regulating the amount of water which is to be permitted to flow from the casing 1, the float 61 is adapted to be adjusted vertically upon the stem 51 of the outlet valve. This vertical adjustment preferably is secured by means of a set screw 63 which extends through a sleeve 64 on the upper end of the float 61 and impinges against the stem 51. In order to render the float 61 air-tight, said float is formed with an inner tube 65 which surrounds the stem 51, as shown. If the float 61 be adjusted high upon the stem 51, the outlet valve will descend against the bushing 44 after a comparatively small quantity of water has escaped from the casing 1; and if the float 61 be adjusted low upon the stem 51, the outlet valve will not contact with the bushing 44 until a comparatively large quantity of water has escaped from the tank. In this way the discharge of water is readily regulated. The lower float 62 preferably is conical in shape so that it will have a tendency to rise readily through the water in the casing 1 when the cord 59 is pulled, whereby the resistance on the part of said float 62 is reduced to a minimum. For the purpose of preventing the accidental overflow of the casing 1 in the event that the inlet valves should get out of order and fail to close, the casing is provided with a plurality of overflow pipes 66, the upper ends 67 of which are disposed at the desired water level in the casing 1, and the lower ends 68 of which extend along the bottom of the casing 1 and pass through the bushing 44 below the outlet valve so as to cause any excess of water in the casing 1 to drain off

through the outlet pipe 43. It will be observed that the upper end of the bushing 44 extends above the bottom of the casing 1, for which reason the overflow pipes 66 can be conducted into said bushing without perforating the bottom of the casing 1, or conducting the pipes 66 outside of said casing.

The improved flushing tank of this invention is strong, simple, durable and inexpensive in construction as well as thoroughly efficient in operation.

What is claimed is:

1. The combination with a flushing tank including an inlet valve, an outlet pipe extending through the bottom of the tank and provided with a valve seat, a valve engaging said seat, a stem extending vertically from the valve, a hollow conical casing surrounding the valve stem and resting on said valve, a vertically adjustable float slidably mounted on the valve stem above the conical casing, and an operating lever pivotally connected with the upper end of the valve stem.

2. The combination with a flushing tank including an inlet valve, an outlet pipe extending through the bottom of the tank and provided with a valve seat, a supporting frame extending above the valve seat and provided with vertically aligned openings, a valve engaging said seat, a stem secured to said valve and slidably mounted in the openings in the supporting frame, a hollow conical casing secured to the valve and surrounding the stem, a float disposed within the supporting frame and slidably mounted on said valve stem, means for locking the float in adjusted position, and an operating lever pivotally mounted on the supporting frame and operatively connected with the upper end of the valve stem.

3. The combination with a flushing tank including an inlet valve, a valve seat secured to the bottom of the tank and provided with interior threads, an outlet pipe engaging the threads of the valve seat, a valve resting on said seat, a supporting frame having vertically aligned openings formed therein, a stem secured to the valve and slidably mounted in said openings, a hollow conical casing resting on the valve, an adjustable float disposed above the conical casing and having a sleeve for the reception of the valve stem, a clamping screw piercing the sleeve and engaging the stem for locking the float in adjusted position, and an operating lever pivotally mounted on the supporting frame and operatively connected with the upper end of the valve stem.

4. The combination with a flushing tank including an inlet valve, of an outlet pipe communicating with the interior of the tank, a valve seat secured to the outlet pipe, a valve engaging said seat, a valve stem connected with the valve, a hollow casing resting on the valve and having its side walls

inclined upwardly in the direction of the valve stem, a vertically adjustable float slidably mounted on said valve stem above the hollow casing, and an operating lever 5 pivotally connected with the upper end of the valve stem.

In testimony that I claim the foregoing

as my own, I have hereto affixed my signature in the presence of two witnesses.

HENRY S. HAWKS.
